WITNESS:

S. G. Taylor

INVENTOR
Chester J. Randall,

BY
Ernest A. Morrison
HIS ATTORNEY

UNITED STATES PATENT OFFICE.

CHESTER J. RANDALL, OF NAUGATUCK, CONNECTICUT, ASSIGNOR TO THE GOODYEAR'S METALLIC RUBBER SHOE COMPANY, A CORPORATION OF CONNECTICUT.

APPARATUS FOR EXHAUSTING THE INTERIOR OF RUBBER ARTICLES.

1,273,112.

Specification of Letters Patent.

Patented July 16, 1918.

Application filed February 4, 1916. Serial No. 76,104.

To all whom it may concern:

Be it known that I, CHESTER J. RANDALL, a citizen of the United States, residing at Naugatuck, county of New Haven, and State 5 of Connecticut, have invented certain new and useful Improvements in an Apparatus for Exhausting the Interior of Rubber Articles, of which the following is a full, clear, and exact description.

10 This invention relates to apparatus used in controlling the interior and external pressure exerted upon articles of rubber, rubber-like, or similar materials, during or prior to the process of vulcanization.

15 Ordinarily, in vulcanizing under the differential of pressure process, the articles, such as for instance, boots and shoes, are built upon hollow perforated forms or lasts. The lasted articles are mounted upon a car, 20 the frame of which is formed of tubing, there being branch pipes of this tubing connected with the interior of the lasts. The loaded car is run into a vulcanizer wherein the outside of the articles is subjected to 25 heat and controllable high pressure. The car tubing is connected usually to an exhaust pump outside of the vulcanizer by means of which the inside of the articles is subjected to a lesser pressure than the outside, this 30 differential of pressure serving to exhaust air, gases, fluids and the like, from the articles.

The present invention provides each car with an independent exhaust device which 35 preferably is automatically brought into action when a predetermined degree of pressure or temperature is attained within the vulcanizer.

30 The invention can be readily understood 40 from the following description taken in connection with the accompanying drawing, in which—

Figure 1 is a sectional view with parts 45 in elevation, showing an apparatus suitable for carrying out one embodiment of the invention.

Fig. 2 is a detail sectional view showing an automatic check valve.

Fig. 3 is a fragmentary sectional view 50 showing a modified form of the valve shown in Fig. 2.

Referring now to the drawing in which like characters designate similar parts, a car is shown comprising a frame 15 formed

of tubing, there being branch pipes 16 of 55 this tubing at intervals to support lasts 17 upon which the articles, in the present instance boots 18, are built, each last being hollow and having perforations that expose the interior of the article to the interior of 60 the last. The car is mounted upon wheels 19 which facilitate the car being run upon a track 20 into a vulcanizer 21, which preferably is pressure tight. A heat medium under pressure is admitted to the vulcanizer 65 through a valve controlled pipe 22.

In carrying out the present embodiment of the invention, the car is equipped with a low pressure or vacuum tank 23 which is preferably permanently secured to the car by 70 brackets 23' and is connected with the interior of the car frame by a pipe 24. Through a valve controlled pipe 25 the tank may be exhausted by suitable apparatus, preferably prior to loading of the car with the lasted 75 articles to be vulcanized. Communication between the interior of the lasts and the tank is controlled by an automatic check valve 26 having a plunger 27 exposed to the medium in the vulcanizer and normally held by a 80 spring 28 to seal the passage in the pipe 24. The plunger is raised against the pressure of the spring when a predetermined degree of pressure of the medium in the vulcanizer is reached and unseals the pipe 24 permitting 85 the vacuum to act upon the interior of the articles through a passage 29 in the plunger. An adjusting screw 30 facilitates varying 90 the tension of the spring to time the opening of the valve as desired.

Should however, it be desired to control the application of the low pressure or the vacuum from the exterior of the vulcanizer, the casing of the valve 26 may be closed as shown at 31 in Fig. 3 and a pipe 32 arranged 95 to conduct pressure from a source of pressure outside the vulcanizer through the closure 31 to open the valve whenever desired.

I do not limit the scope of the invention to the utilization of vacuum or low pressure 100 during the vulcanizing process as it is evident the vacuum tank may be brought into action prior to the vulcanizing process either while the car is in or out of the vulcanizer.

I do not limit the scope of the invention to 105 timing the opening of the check valve 26 by a rise in pressure, since the valve may be equipped with temperature controlling

means operating to open the valve at a pre-determined degree of temperature.

Furthermore, I do not limit the invention to the equipment of each car with a vacuum tank, since the vacuum tank may be installed in the vulcanizer or even outside of the vulcanizer and either automatically brought into action or not, as desired, to being simply necessary for the practice of the invention that one or more cars be connected with a low pressure or vacuum tank.

Having thus described my invention, what I claim and desire to protect by Letters Patent is:

- 15 1. An apparatus of the class described comprising a portable frame, a perforated hollow last communicated with the interior of said frame, a low pressure or vacuum tank assembled as a unit with said frame, and a valve controlled pipe connecting the interior of said frame with the interior of said tank.
- 20 2. An apparatus of the class described comprising a vulcanizer, means for supplying pressure in the vulcanizer, a portable frame in the vulcanizer, a perforated hollow last on said frame in communication with the interior of said frame, a low pressure or vacuum tank assembled as a unit with said frame, a pipe connecting the interior of said

frame with said tank, a valve in said pipe, and means for operating the valve.

3. An apparatus of the class described comprising a vulcanizer, means for supplying pressure in the vulcanizer, a hollow frame in the vulcanizer, a perforated hollow last on said frame in communication with the interior of said frame, a low pressure or vacuum tank, a pipe connecting the interior of said frame with said tank, and means controlling said pipe to automatically establish communication between the interior of said frame and said tank at a predetermined stage in the vulcanizing process.

4. An apparatus of the class described comprising a vulcanizer, means for supplying pressure in the vulcanizer, a hollow frame in the vulcanizer, a perforated hollow last on said frame in communication with the interior of said frame, a low pressure or vacuum tank assembled as a unit with said frame, a pipe connecting the interior of said frame with said tank, and a check valve in said pipe adapted to automatically open when the pressure in said vulcanizer reaches a predetermined degree.

Signed at Naugatuck, Conn., this 1st day of February, 1916.

CHESTER J. RANDALL.
